The ornamental design for a medical patch, as shown and described.

DESCRIPTION

(51) **LOC (10) Cl.** 24-04

FIG. 1 is a front view of a medical patch of the present invention, also showing instructions for use.

(52) **U.S. Cl.**

FIG. 2 is a rear view thereof;

USPC D24/189

FIG. 3 is a top plan view thereof;

(58) **Field of Classification Search**

FIG. 4 is a bottom view thereof;

USPC D24/189; 602/41-47, 53, 54, 57, 58;
128/DIG. 26

FIG. 5 is a right side view thereof;

See application file for complete search history.

FIG. 6 is a left side view thereof; and,

FIG. 7 is an enlarged sectional view of the medical patch taken along line 7-7 of FIG. 1.

(56) **References Cited**

The features shown only in dotted lines (. . .) depict environmental subject matter only and form no part of the claimed design.

U.S. PATENT DOCUMENTS

The features surrounded by dashes and dotted lines (. . . .) are part of the claimed design.
